UNITED STATES PATENT OFFICE.

JAMES CAMROD LEDBETTER, OF NEW YORK, N. Y., ASSIGNOR TO THE PROSPERITY COMPANY, INC., OF SYRACUSE, NEW YORK, A CORPORATION OF NEW YORK.

GARMENT PRESS.

Application filed November 16, 1925. Serial No. 69,235.

This invention relates to presses and more particularly to improvements in press operating mechanism useful for example in garment presses, ironing and laundry presses and the like.

An object of the invention is to produce an improved pressing machine which is comparatively small and compact in structural arrangement to the end that a weight balancing mechanism may be mounted on the inside of the press frame thus improving the appearance of the pressing machine and requiring less floor space therefor.

A further object of the invention is to produce a pressing machine having improved press operating mechanism comprising relatively few parts so as to reduce the cost of manufacture and simplify assembly operations.

The accompanying drawing illustrates an embodiment of the invention with the press jaws closed. The press is shown open in dotted lined position, the illustration being partially diagrammatic to simplify the illustration.

Referring now more particularly to the diagram or drawing forming a part of this disclosure, there is shown a press frame 10 carrying the usual work table 11 which holds the work on the table to prevent it from accidentally getting into the operating mechanism. The press frame supports a stationary buck 12 against which a movable head 13 raises and lowers. The pressing members or jaws 12 and 13 open up, as by lifting the head jaw 13 to receive the work which is spread upon the buck 12 and the mechanism for raising and lowering the head 13 is improved in many respects over pressing machines now in use.

A press lever comprises a long curved lever 15 pivoted at 16 on the frame 10 and the lever 15 more particularly consists of a lower vertical arm 17 and a forward horizontal arm 18 attached by a suitable spring compensating means 19 to the head 13. The press lever 15 is preferably shaped to extend it vertically downwardly within the press frame 10 when the press is closed and when the press is open the lower arm 17 of

the press lever moves forwardly towards the table 11 as indicated in dotted lines. A head operating handle is made on the forward end of the lever arm 18 for the purpose of facilitating closure of the press in case the operator wishes to draw the head down by hand.

A vertically mounted swing arm 20 stands in the press frame with its lower end pivotally connected to the frame by a pin 21 and with its upper end connected to the lower arm 17 of the press lever 15. The connection between the upper moving end of the swing arm 20 and the lower end of the press lever 15 consists of relatively movable means as for example a pin 22 which is fixed in the upper end of the swing arm 20 and this pin floats in a slot 23 made in the lower end of the press lever 14. The fact that the swing arm 20 has its lower end pivotally connected to the arm and the fact that the press lever 15 is pivotally mounted on the shaft 16 requires that some suitable movable connection be employed to operatively hook up the two arms 17 and 20. The swing arm 20 is employed for transmitting motion and power from a pedal to be described to the press lever 15 and is employed as well for aiding in counterbalancing the press head.

A weight arm 25 is carried on the upper end of the swing arm 20 and projects upwardly at an angle toward the front of the press. A weight 26 is fixed on the weight arm. This weight arm tends to gravitate downwardly thereby urging the swing arm 20 to move clockwise thus tending to lift the press jaw 13 and open the press. The function of the weight 26 is to balance the heavy head 13 and this weight is placed under the press within the frame out of the way to permit the machine to be made small and compact in size.

A press pedal 28 has its front end equipped with a foot piece 29 located down close to the floor while its rear end is pivoted near the upper end of the link 20 on the pin 30. In this way the pedal 28 sets at an angle in the press with its upper end connected at 30 to the press closing mechanism while

its lower pedal end 29 is close to the floor. The pedal end 29 undergoes a relatively short movement in opening and closing the press and therefore an operator is not required to lift his foot high off the floor to reach the pedal.

A kick-off pedal embodies a link or arm 32 having one end pivoted at 33 in the press frame and the other end pivoted at 34 to the main pedal 28. The link 32 is made in the form of a kick-off pedal and to this end a pedal arm 35 is made integrally with the link 32 and extends forwardly and to one side of the pedal 29. The kick-off pedal 35 is made with a foot piece 36 which is depressed to produce an upward lift on the pedal 28 to break the toggle structure 28-32 to initiate the press opening motion. The pedal 28 together with the link 32 constitutes a toggle which breaks upwardly as shown in dotted line diagram to allow the press head 13 to open under the influence of the weight 26.

In the operation of this pressing machine, work is placed on the buck 12 when the press stands in open dotted line position. The operator now closes the head by hand or by foot power or by both. Light pressure on the pedal 29 causes the link 32 to move downwardly from dotted line position to full line position shown in the drawing thereby causing the pivot point 34 to travel downwardly past a straight line defined between the two pivot points 33 and 30 which is to say that the toggle 28-32 locks by action of the pivot pin 34 having moved past the center line of the toggle. In other words the toggle comprising the pedal 28 and link 32 reaches over-straightened position to lock the press closed under compression.

In this way the press jaws remain closed tight under compression and are held in that position by the locked toggle 28-32 until such time as the operator steps upon the foot piece 36 of the kick-off pedal to break the pivot point 34 upwardly past the aforesaid center line drawn between the two points 30 and 33 whereupon the press is permitted to open.

A press is therefore produced which has operating means, i. e. press opening and closing instrumentalities which includes a pedal, the link portion 28 of which, extends rearwardly and upwardly at an angle to connect with the swing arm 20 above its frame pivot 21, while the front end of the pedal is disposed in a low position convenient to one's foot. The upper and rear end of the pedal pivotally connects with the swing link 20 at a point between its two pivot points 21 and 22. Any suitable means, such as the link or arm portion 32, swingably mounts the front end of the main pedal link 28 in the frame, and this means also includes a kick-off or press opening pedal.

The two arms or links 17 and 20 form a toggle pivoted in the frame at 16 and 21 and the pedal 28 is connected therewith at some point intermediate the said toggle pivots 16 and 21. Any suitable counterbalance weight 70 means, such as 25-26, cooperates with the toggle 17-20 to balance the opening and closing movement of the press.

A sliding pivot means, such as a pin and slot connection 22-23, is included in the 75 press operating mechanism by which relative movement is attained between moving parts in order that one end of the press lever, say the arm 17, may perform the function of a toggle. This sliding pivot means may be 80 placed at any suitable point.

What I claim is:

1. A pressing machine including a frame and comprising in combination, press jaws which open and close on the work; a curved 85 press lever pivotally carried substantially at its center on the frame, and having its upper end disposed in a horizontal plane, and having its lower end disposed in a vertical plane; one of the aforesaid press jaws being attached to the upper horizontal end of the press lever, a swing arm having its lower end pivotally mounted on the frame, means connecting the upper end of the swing arm to the lower end of the press lever, a counterbalance weight mounted on the swing arm underneath the press jaws, a pedal connected with the swing arm, and means mounting the pedal movably in the frame to open and 90 close the press.

2. A pressing machine including a frame and comprising in combination, press jaws which open and close on the work; a curved press lever pivotally carried substantially at its center on the frame, and having its upper 105 end disposed in a horizontal plane, and having its lower end disposed in a vertical plane; one of the aforesaid press jaws being attached to the upper horizontal end of the press lever, a swing arm having its lower end pivotally mounted in the frame, means connecting the upper end of the swing arm to the lower end of the press lever, a pedal having one end thereof connected with the swing arm, and a kick off device pivotally 110 mounted in the frame and connected with the pedal.

3. A pressing machine comprising in combination, a frame, cooperating press jaws carried thereby, a press lever pivoted in the frame and attached to one jaw to raise and lower it in relation to the other jaw, a vertical swing arm having its lower end pivotally mounted on the frame, means connecting the upper end of the swing arm to the press lever, and operating means including a pedal pivotally connected to the swing arm above the frame pivot thereof and also including means movably mounting the pedal to force the pedal rearwardly as it is depressed.

4. A pressing machine comprising in combination, a frame, cooperating press jaws carried therewith, a press lever pivoted in the frame and attached to one jaw to raise and lower it in relation to the other jaw, a vertical swing arm having its lower end pivotally mounted on the frame, a weight arm integrally carried near the upper end of the swing arm and projecting forwardly inside the frame, a counter weight mounted on the weight arm, means connecting the upper end of the swing arm to the press lever, and operating means including a pedal connected to the swing arm and to the frame adapted to cause the upper end of the swing arm to work back and forth.

5. A pressing machine comprising in combination, a frame, cooperating pressing jaws, a press lever pivoted in the frame with its upper forward end attached to one of the press jaws to open and close it, a vertical arm having its lower end pivotally attached to the frame and its upper end connected to the rear and lower end of the press lever, a pedal including a foot piece disposed at the front of the press and having said foot piece placed low down close to the floor and having its rear end extending upwardly and connected to the upper end of the vertical arm, a link having one end pivotally connected on the frame and its other end connected with the pedal and forming a toggle therewith, and means to balance the opening and closing press jaw.

35. 6. A pressing machine comprising in combination, a frame, cooperating pressing jaws, a press lever pivoted in the frame with its forward end attached to one of the press jaws to open and close it, a vertical arm having its lower end pivotally attached to the frame and its upper end connected to the rear and lower end of the press lever, a pedal including a foot piece disposed at the front of the press and having said foot piece placed low down close to the floor and having its rear end extending upwardly and connected to the upper end of the vertical arm, a link having one end pivotally connected on the frame and its other end connected with the pedal and forming a toggle therewith, a weight arm carried on the upper end of the vertical arm and directed upwardly toward the front of the machine, and a weight mounted on the weight arm adapted to balance the movable press jaw.

7. A pressing machine as defined in claim 6 further distinguished by a kick-off pedal carried with the end of the link and adapted to break the toggle and initiate the opening of the press.

8. A pressing machine comprising in combination, a frame, cooperating press jaws, one of which is fixed in the frame and the other being movable; a curved press lever pivoted in the frame, and having its upper

forward end attached to the movable jaw, and its lower end extending vertically downwardly by the frame; a vertical swing arm having its lower end pivoted in the rear of the press frame, a pin and slot connecting together the swing arm and the lower end of the press lever, a weight arm carried on the swing arm and extending toward the front of the machine, a weight mounted on the weight arm and acting to urge said swing arm forwardly with a resulting tendency to lift the movable jaw, a treadle having its rear end operatively connected to the press lever and swing arm, and means movably supporting the front end of the pedal on the frame to cause the pedal to move rearwardly as it is depressed.

9. A pressing machine comprising in combination, a frame, cooperating press jaws one of which is fixed in the frame and the other being movable; a curved press lever pivoted in the frame, and having its upper forward end attached to the movable jaw, and its lower end extending vertically downwardly into the frame; a treadle placed angularly within the frame with its upper rear end pivotally cooperating with the press lever, a foot piece carried on the lower front end of the treadle, means movably mounting the front end of the pedal in the frame to force the pedal rearwardly as the pedal is depressed, and a counterbalance weight means pivotally connected with the frame and connected to the lower end of the press lever.

10. A press comprising jaws and a frame, operating means carried with the frame by which the press is opened and closed, the operating means including: a toggle embodying links connected together at their adjacent ends, and the outer ends of said links being pivotally supported on frame pivots, and including a sliding pivot connection; means operated by the toggle to open and close the press, and means to work the toggle.

11. A press comprising jaws and a frame, operating means carried with the frame by which the press is opened and closed, the operating means including: a toggle embodying links connected together at their adjacent ends, and the outer ends of said links being pivotally supported on frame pivots, and including a sliding pivot connection; means operated by the toggle to open and close the press, and means to work the toggle including a pedal extending from a low position at the front of the press upwardly at an angle toward the rear with its upper end pivotally connected with the toggle between the frame pivots, and means movably mounting the pedal in the frame to impart a rearward motion to the pedal when it is depressed.

12. A press comprising jaws and a frame, operating means carried with the frame by

which the press is opened and closed, the operating means including: a vertical toggle embodying links connected together at their adjacent ends, and the outer ends of said 5. links being pivotally supported on frame pivots, and including a sliding pivot connection; means operated by the toggle to open

and close the press, and means to work the toggle, and jaw counterbalance means including a weight arm carried with the vertical toggle extending therefrom toward the front of the press, and a weight on the arm.

In testimony whereof I affix my signature.
JAMES CAMROD LEDBETTER.
